UNITED STATES PATENT OFFICE.

ISADORE D. WOLFSON, OF NEW YORK, N. Y.

NECKTIE.

Application filed April 7, 1926. Serial No. 100,424.

This invention relates to neckties and more particularly to neckties of the bow or bat wing type.

An object of the invention is to provide a device of this character in which the bow portion of the tie is secured intermediate its ends across and at right angles to a neckband portion of the same tie.

It is a well known fact that in tying a bow tie the two end portions are positioned vertically with relation to the neckband. This is usually done by tying a knot in the tie so as to position the two ends vertically, one end being preferably longer than the other, and the two ends are then folded and tied to form a bow which will be in horizontal position and longitudinal with relation to the neckband of the tie, and it is therefore the primary object of my invention to provide a tie having a bow, or strip to form a bow, secured intermediate its ends at right angles to the neckband portion of the tie so that when the latter is around the neck of the user the end portions are vertical.

A further object is to provide a tie in which the bow portion of the tie is secured intermediate its ends to an elastic section of the neckband, the latter being capable of adjustment longitudinally and having suitable coupling means to connect the same around the collar, leaving the bow portion of the tie in proper position for tying.

With these and other objects in view, the invention consists in certain novel features of construction and combinations and arrangements of parts, which will be more fully hereinafter described and pointed out in the claim.

Figure 1 is a plan view of my improved tie, all portions thereof laid flat;

Figure 2 is an exaggerated view in section on the line 2-2 of Figure 1;

Figure 3 is a perspective view showing the tie with the bow formed ready for use.

While my apparatus as a whole constitutes a necktie, as a matter of fact it constitutes two distinct portions of a necktie, to which for clearness of description I shall give different terms.

1 represents the neckband portion of the tie and 2 the bow portion of the tie. This neckband portion is preferably made of the same material as the bow portion 2 and is capable of longitudinal adjustment through

the medium of a coupling slide 3. A strip 55 of elastic 4 is secured to one end of the neckband 1 and a hook 5 is provided on one end of the neckband with an eye 6 at the other end to facilitate the coupling of the same around the collar of the user. 60

The bow portion 2 is preferably of the bat wing type but it may be of any other type and has a narrow intermediate portion 8 which is secured to the elastic strip 4.

The strip 2 or bow portion is disposed at 65 right angles to the neckband portion 1, and while of course the invention is not limited to any particular means of coupling the two portions of the tie together I preferably provide at least two coupling means 7 in parallel as shown so as to prevent the possibility of pivotal or twisting movement. This coupling means may comprise ordinary stitching or any other suitable fastening mechanism. 75

The point of attachment between the parts is nearer one end of the strip 2 than the other so that one end of the bow portion is slightly longer than the other which is convenient for tying a presentable bow. The 80 bow may be tied before the device is placed around the collar, or it may be tied after the band 1 is secured around the collar and the tying of the bow is well within the scope of any user of neckties. After the bow is 85 once tied to the satisfaction of the user it need not be again tied or untied as the device can be placed on the collar or removed therefrom, as will be readily understood.

With my improved necktie I not only provide a tie which can be easily tied in bow form but I provide a necktie which is made up of a strip located at right angles to the neckband so that this strip will be positioned vertically, ready for tying when the band is 95 in position on the neck; and I therefore believe that I am enabled to provide an article of this character which is not only superior in its structural formation to analogous devices but it presents a superior appearance 100 and is much more convenient for the user of ties who desires to make his own bow.

Various slight changes and alterations might be made in the general form of the parts described without departing from my 105 invention and hence I do not limit myself to the precise details set forth but consider myself at liberty to make such slight changes

and alterations as fairly fall within the spirit and scope of the appended claim.

I claim:

5 A necktie, comprising a neckband, an elastic strip at one end of the neckband, coupling devices at the respective ends of the neckband, a strip adapted to be tied into

bow form, said strip narrowest at its intermediate portion, and means securing the intermediate portion of the last mentioned strip to the elastic portion of the neckband and at right angles thereto.

10 ISADORE D. WOLFSON.
